Fig. 5.

UNITED STATES PATENT OFFICE.

PAUL JOSEPH FORSYTHE, OF ELDORADO, KANSAS.

SIGNAL.

Application filed July 25, 1921. Serial No. 487,392.

To all whom it may concern:

Be it known that I, PAUL J. FORSYTHE, a citizen of the United States, residing at Eldorado, in the county of Butler and State of Kansas, have invented new and useful Improvements in Signals, of which the following is a specification.

This invention relates to signaling devices, particularly to direction indicators for vehicles, and has for its object the provision of a signal device adapted to be mounted upon a motor vehicle and operable whereby to apprise following traffic of any intended change in the direction of travel or of a contemplated stop, the device having the advantage of facilitating traffic and reducing the danger of accident.

An important object is the provision of a device of this character which is electrically operated whereby the action is all controlled by the manipulation of suitable switches located upon or near the steering column or at any suitable location convenient to the operator.

A further object is the provision of a signal of this character which is adapted for use at night as well as by day, automatic switch means being provided for energizing certain signal lights simultaneously with the movement of semaphore arms, the lighting means being of course inoperative in day time.

Still another object is the provision of a device of this character which is all housed within a single casing which also carries a tail light and which furthermore carries a flood light adapted to illuminate the roadway at the rear of the machine in case it is desired to back.

An additional object is the provision of a device of this character which will be simple and inexpensive in manufacture, easy to install and operate, highly efficient in use, durable in service, and a general improvement in the art.

With the above and other objects and advantages in view, the invention consists in the details of construction to be hereinafter more fully described and claimed and illustrated in the accompanying drawings in which—

Figure 1 is an elevation of my device,

Figure 2 is a similar view with the cover plate removed,

Figure 3 is a vertical longitudinal section taken at right angles to Figure 2;

Figure 4 is a vertical sectional view taken in advance of the plane of Figure 2 and showing the switch mechanism,

Figure 5 is a horizontal sectional view taken above the switch mechanism, and

The remaining figures are detail views.

Referring more particularly to the drawings, I have shown my device as comprising an upright casing 10 carrying an arm 11 which might be a bracket or which may be adapted for connection with a bracket 12 secured upon some convenient location on the vehicle. Associated with this casing 10 are arms 13 which are slotted, as shown, whereby license plates may be carried thereby. Located within the bottom portion of the casing is a suitable socket 14 carrying an incandescent bulb 15. The casing 10 is covered by a removable cover 16 held in place by any suitable means as by means of screws 17 passing through lugs 18 on the cover. At the lower part of the cover is an opening covered by red glass 19 located near the bulb 15 and this constitutes the tail light structure.

One side of the casing is provided with an opening 20 covered by clear glass whereby white light from the bulb 15 will shine upon the license tag or tags, as required by law. The socket 14 is connected with the lighting wiring of the car in the ordinary manner.

At the intermediate portion of the cover 16 I provide an opening covered by plain glass 21 and within this opening is mounted a reflector 22 at the center of which is disposed a socket 23 carrying a bulb 24. This socket 23 is connected in circuit with the source of current of the car and with a suitable independent control switch, not shown, mounted at some convenient point within reach of the operator whereby the bulb 24 may be energized to throw a flood light to the rear of the vehicle for illuminating the roadway when it is desired to back.

Secured against the back wall of the casing 10 are two solenoids 25 and 26 with which are associated slidable cores or armatures 27 and 28, respectively. Secured within the upper portion of the casing is an arm 29 provided with a bearing for one end of a horizontally disposed shaft 30 which has its other end journaled in the back of the casing. Secured upon this shaft is a semaphore blade 31 which is normally disposed within the casing in vertical depending po-

sition and which is adapted to swing into horizontal position through a slot 32 in one side of the casing. Also secured upon this shaft is an arm 33 with which is pivotally connected one end of an arcuate link 34 with the intermediate portion of which is pivoted a link 35 pivotally connected with the core or armature 27.

Rotatable upon the shaft 30 is a sleeve 36 upon which is rigidly secured a semaphore blade 37. Also secured upon this sleeve 36 is an arm 38 with which is pivotally connected an arcuate link 39 which is in turn pivotally connected intermediate its ends 15 with a link 40 pivotally connected with the core or armature 28. The semaphore blades 31 and 37 may bear the legends "Right" and "Left," respectively, and may be colored the same or have different colors as 20 may be preferred, so as to attract attention. The casing is also provided with a slot 41 through which the semaphore blade 37 may pass when it swings to horizontal position.

The solenoids 25 and 26 have their windings connected in circuit with a suitable source of current which would ordinarily be the storage battery of an automobile and included in this circuit is a suitable switch mechanism which might be of special construction but is herein illustrated as being merely diagrammatic. It is of course necessary that an independent switch be provided for each solenoid and this switch mechanism is entirely independent of any 30 switches which might be used for controlling the energization of the tail light 14 and the flood light bulb 24. Ordinarily both of the semaphore blades hang downwardly and are confined entirely within the 35 casing. In case it is desired to turn in one direction or the other the operator closes the proper switch which will result in energization of the proper one of the solenoids 25 or 26. When a solenoid is energized the core 27 or 28 thereof will be drawn upwardly thereto. It should be stated that the arcuate links 34 and 39 are formed with notches 42 which are normally engaged 40 upon a keeper 43 mounted within the casing for holding the semaphore blades in their downwardly extending position and preventing them from movement. When a selected solenoid is energized, as above described, and the core therein is moved upwardly, the first result will be upward movement of the associated arcuate link 34 or 39 so as to release the notch 42 from engagement with the keeper 43. The continued movement of course results in swinging of 45 the arm 33 or 38, as the case may be, resultant rotation of the shaft 30 or sleeve 36 and this will of course result in upward swinging movement of the desired semaphore blade to horizontal or signaling position. When the switch is subsequently

opened the semaphore blade previously raised will gradually descend to normal or initial position. It is of course to be understood that when the operator of the vehicle intends to turn to the right he closes the 70 switch which will cause the right hand semaphore blade to swing to signaling position and when he intends to turn to the left he closes the other switch for causing the left hand semaphore blade to be elevated. 75 In case of an intended stop the operator may move both switches or a separate switch connected in series therewith for causing elevation of both semaphore blades. 80

In order to adapt the device for night use I provide sockets 44 and 45 suitably mounted within the casing back of openings in the cover thereof, these openings being covered by colored glass panes 46 and 47. I also provide a socket 48 mounted within the casing back of an opening covered by a red glass 85 49. The arm 29 supports on its upper surface the ends of a pair of oppositely inclined arms 48' and 49' respectively and said arms 48' and 49' are arranged to define a substantially V-shaped yoke. The arm 48' is insulated from the arm 49' as clearly shown at 49'' but both arms 48' and 49' are in the circuit of the lighting system. The free end of the arm 48' is designed to 90 carry, but insulated therefrom, a contact 50 and a noninsulated stationary contact 51 engageable with the contact 50. This end of the arm 48' also carries contacts 50' and 51', both of which are insulated from the arm 48', and are engageable with each other. When the semaphore blade 31 is raised, the above mentioned contacts are interposed in the circuit so that the engagement of the contacts will cause the bulb 52 within the 95 socket 44 to be energized. The energization of this bulb of course shows a colored light to the rear and I also provide an opening 53 within one side of the casing whereby light from this bulb 52 will shine upon the semaphore blade 31. The free end of the arm 49' is designed similar to the free end of the arm 48' and carries contact 54 which is insulated therefrom and a non-insulated contact 55. The contacts 54 and 55 are 100 engageable with each other. The arm 49' also carries contacts 54' and 55', engageable with each other but insulated from the arm. When the semaphore blade 37 is raised to signaling position, these contacts are closed, being interposed in the circuits with the socket 45 carrying a bulb 56. The engagement of the contacts 54, 55, 54' and 55' will of course result in energization of the bulb 56 which 105 will cause a colored light to be displayed through the pane 47 and it is also preferable to provide an opening 57 in the side of the casing whereby this light will shine upon a semaphore blade 37. Suitably connected in circuit with both sets of these contacts is a 110 115 120 125 130

socket 48 which carries a bulb 58 so that when both semaphore blades are raised, by closing of the proper switch mechanism by the driver, not only the bulbs 52 and 56 will 5 be energized but also the bulb 58 whereby a red light shines through the pane 49 in addition to the colored lights at the panes 46 and 47. It is of course preferable to interpose a suitable control switch in the circuit 10 whereby all the lighting apparatus will be inoperative in daytime.

From the foregoing description and a study of the drawings it will be apparent that I have thus provided a simply constructed and consequently inexpensive device whereby the operator of a motor vehicle may quickly and easily signal any intention to change the direction of his travel or to stop whereby to apprise following traffic 15 of the intention in order to avert accidents and traffic congestion. It will be noted that my device amply provides for all contingencies and is fully operative regardless of whether its use be desired by day or by 20 night.

While I have shown and described the preferred embodiment of my invention, it is of course to be understood that I reserve the right to make such changes in the form, 25 construction and arrangement of parts as will not depart from the spirit of the invention or the scope of the subjoined claims.

Having thus described my invention, I claim:

35 1. A signal comprising a casing, a bracket mounted on one wall thereof, a rotatable shaft mounted between the bracket and the casing wall, a sleeve rotatably mounted on the shaft, semaphores carried by the shaft and sleeve respectively, links depending from the shaft and sleeve provided with notched edges, a keeper positioned beneath the shaft and provided with a central apertured web, a locking flange on either side thereof, the links depending from the shaft and sleeve operating through the aperture of the web to slidably engage their respective flanges, and means to move the semaphores into operative position.

50 2. A signal comprising a casing, a bracket

mounted on one wall thereof, a rotatable shaft mounted between the bracket and the casing wall, a sleeve rotatably mounted on the shaft, semaphores carried by the shaft and sleeve respectively, crank arms carried by the shaft and sleeve and extending therefrom on opposite sides, arcuate links pivotally carried by the crank arms, said links being provided with notched edges, a common keeper positioned centrally beneath the shaft, said keeper including an apertured, upstanding web, a locking flange on either side thereof, the pivoted links depending from the crank arms operating through the aperture of the web from opposite sides thereof in spaced apart parallel planes and slidably engaging their respective flanges, and means to move the semaphores into a visible position.

3. A signal comprising a casing, a bracket 70 mounted on one wall of the casing interiorly thereof, a rotatable shaft journalled between the wall and the bracket, a sleeve rotatably mounted on the shaft, semaphores carried by the shaft and sleeve respectively, locking 75 means carried by each of the semaphores whereby to maintain them in an inoperative position, a common keeper engaging both of said locking means, and means to rotate the shaft and sleeve independently to actuate 80 the semaphores.

4. A signal comprising a casing, a bracket mounted on one wall of the casing interiorly thereof, a rotatable shaft journalled between the wall and the bracket, a sleeve rotatably 85 mounted on the shaft, semaphores carried by the shaft and sleeve respectively, locking links pivotally carried by the shaft and sleeve respectively and designed to operate in over-lapping relation in spaced apart 90 parallel vertical planes, a common keeper positioned centrally beneath the shaft and adapted to engage the locking links whereby to maintain the semaphores in an inoperative position and means to rotate the shaft 95 and sleeve to actuate the semaphores.

In testimony whereof I affix my signature.

PAUL JOSEPH FORSYTHE.
